UNITED STATES PATENT OFFICE.

DAVID P. WEIR, OF RATHDRUM, IDAHO.

RATCHET DEVICE.

Application filed February 6, 1926. Serial No. 86,611.

My invention pertains to ratchet devices in which pinions operate in conjunction with other gears to produce a ratchet effect.

- The object of my invention is to provide a ratchet device, that is economical in construction and reliable in operation, with the friction of its engaged parts reduced to a minimum at all times and the clicking noise of the pawls eliminated.
- 10 The invention belongs to that class of ratchets where the pinions may revolve freely when not engaged in a locking operation and has reference to certain novel features fully explained herein and includes 15 a pinion retainer adapted to oscillate.

With these and other objects in view, the invention consists of the combination and arrangement of parts as described herein, pointed out in the claims and illustrated in 20 the drawings in which,

- Fig. 1, is a plan view of a shaft secured to a frame, with the ratchet mechanism attached thereto and incased in a housing; Fig. 2, is an enlarged open view of the 25 ratchet mechanism, showing the ratchet gears as assembled on a sleeve, the sleeve being rigidly secured to a broken away end section of a shaft; Fig. 3, is a sectional view taken horizontally on the line 3—3 of Fig. 30 2; Fig. 4, is a face view of one of the co-operating gears; Fig. 5 is a face view of the pinion retainer showing positions of projection stops and pinions assembled; Fig. 6, is a face view of the co-operating mutilated 35 gear.

I have shown a frame (Fig. 1) having a shaft 8 rotatably mounted thereon (the frame and shaft being no part of my invention). Rigidly secured to one end of the 40 shaft 8 is a sleeve 10 (Fig. 3). One end of the sleeve 10 is provided with a flanged head 12 and projecting shoulders 11. The opposite end of the sleeve 10 is threaded for the reception of the nut 13, and is also provided with cut-in grooves 10^a for the 45 reception of stops 13^b on the lock washer 13^a, and is further provided with an opening 10^b extending through the sleeve 10 for the reception of the cotter-pin 13^c.

- 50 Rigidly secured to one end of the sleeve 10 (Figs. 2 and 3) by means of the sleeve 10 entering and passing through the opening 15 from the back side and the shoulder stops 11 being fitted into the key seats 15^a (Fig. 4) 55 is the driven gear 14. The outer front face

of the gear 14 is provided with cogs 16, uniformly spaced. The inner front face 17 of the gear 14 is smooth and extends a little beyond the cogs 16.

Loosely occupying a central position on the sleeve 10 (Figs. 2 and 3) by the sleeve 10 entering and passing through the opening 22 from the back side (Fig. 5) is the plate 18. Uniformly spaced near the outer face of the plate 18, on the front side, are 60 projecting coupling stops 19. Also uniformly spaced within the plate 18 are openings 20. The opposite interior and exterior sides of the openings 20 are parallel. Cut into the plate 18 through the center of 70 each of the parallel sides of the openings 20 and extending from the back side wall through the plate 18 are grooved tracks 21 (Fig. 3) adapted for the reception of 75 slideable bushing caps 21^a. In the center of the bushing caps 21^a are spindle holes 21^b extending well through the center thereof. Assembled within the openings 20, by means of the spindle arms 24 rotatably occupying 80 the spindle holes 21^b are pinions 23. The spindle ends of the pinions 23 are formed with convex faces. The pinions 23 are provided with cogs 25 and mesh with the cogs 16 of the gear 14 at all times.

Rotatably engaging the sleeve 10 near the outer end (Figs. 2 and 3) by the sleeve 10 entering and passing through the opening 31 from the front side (Fig. 6) is the mutilated drive gear 26. Gear 26 is provided at regular intervals with cogs 28 adapted to mesh with cogs 25 of the pinions 23. Between the cogs 28 of the gear 26 are recesses 29. Near the outer front face of the gear 26 are projecting coupling lugs 27 adapted to engage the stops 19 of the plate 18 (Fig. 2). 95 The inner front face 30 of the gear 26 is smooth and extends a little beyond the cogs 28. The back side of the gear 26 is provided with threaded screw bolt holes 32 (Fig. 3) for the reception of screw bolts 33 (Fig. 2), 100 by means of which any medium of powder transmission may be attached, as the hand crank 9 (Fig. 1). Thus the stops 27 and the teeth or cogs 28 are arranged on the gear 26 in such manner that the drive gear 105 26 may be turned in one direction without clutch engagement, while opposite turning movement of gear 26 effects the engagement of the parts.

The washer 13^a with stops 13^b slips over 110

the end of the sleeve 10 and occupies a position loosely engaging the outer side of the gear 26. The stops 13^b slide into the cut-in grooves 10^a and prevent the washer 13^a from 5 revolving on the sleeve 10.

The gear 14, plate 18 and gear 26 are held in their respective positions by means of the nut 13 being adjusted on the outer end of the sleeve 10 adjacent to the washer 13^a.

10 When the propelling power is applied revolving the gear 26 forward (to the right in the present instance) the cogs 28 are brought into mesh with the cogs 25 of the pinions 23 and simultaneously the rear lugs 15 27 of the gear 26 engage the stops 19 of the plate 18 forcing the plate 18 to revolve with the gear 26 (Fig. 2). This prevents the rotation of the pinions 23 during this operation and thereby forces the gear 14 to rotate 20 with the gear 26.

The pinions 23 adjust themselves automatically by means of the adaptability of the bushing caps 21^a to slide back and forth in the grooved tracks 21.

25 When the shaft 8 and consequently the gear 14 continue to revolve forward while the gear 26 is stopped the plate 18 is carried forward engaging the stops 19 with the front lugs 27 of the gear 26 allowing the 30 pinions 23 to occupy positions within the recesses 29, and to idly revolve while in that position. When the gear 26 is revolved backward (to the left in the present instance) the front lugs 27 of the gear 26 are

brought into clutched engagement with the 35 coupling stops 19 of the plate 18, thus leaving the pinions 23 occupying positions within the recesses 29, thereby forcing the plate 18 to revolve with the gear 26 and the pinions 23 to idle and revolve around on the 40 gear 14, consequently allowing the gear 14 to remain idle during this operation.

What I claim is:—

1. The combination with a shaft having a driven gear wheel mounted thereon, of a 45 mutilated drive wheel, an intermediate plate, pinions mounted in said plate and engaging the driven gear wheel, and coacting coupling means on said drive wheel and plate.

2. The combination with a shaft having a sleeve adapted to rotate therewith and a driven gear fixed to the sleeve, of a mutilated drive gear mounted on the sleeve, an intermediate plate, bevel pinions revolvably mounted in said plate for coaction with said 55 gears, and coacting coupling devices on said drive gear and said plate.

3. The combination with a shaft end having a fixed bushing and a driven gear fixed to the bushing, of a mutilated drive gear 60 mounted on the bushing, an intermediate plate having slots therein and bevel pinions journaled in the plate and occupying said slots for coaction with said gears, and complementary clutch lugs and stops on said 65 drive gear and plate.

In testimony whereof I affix my signature.
DAVID P. WEIR.
